LIQUID FUEL BURNING APPARATUS

William J. Smith, Lakewood, Ohio, assignor to
Cleveland Steel Products Corporation, Cleve-
land, Ohio, a corporation of Ohio

Application June 24, 1931. Serial No. 546,504

11 Claims. (Cl. 175—115)

This invention relates to liquid fuel burning apparatus and more particularly to means for igniting the fuel. It is well known that the best and most efficient means for igniting liquid fuel is an electric spark but, in spite of this fact, no safe and practical means for making use of the electric spark for igniting liquid fuel has been heretofore developed for use in connection with liquid fuel burners, such as furnaces. In many types of liquid fuel burning devices, especially those making use of a fuel distributing fan or blower, a fine mist of liquid fuel is discharged against a refractory member and the fuel so collected on this member is ignited.

One disadvantage heretofore encountered in the use of spark gap electrodes is that the electrodes were not properly arranged with respect to the hearth and would become shorted, due to carbon deposits, and when the demand was made for heat the liquid fuel gasified upon its contact with the refractory member if it was hot and as a result when the electrodes eventually did spark upon the breakage of the carbon deposits, a violent explosion occurred.

One of the objects of the present invention is to provide spark ignition means for use in connection with liquid fuel burning apparatus which will function quickly and efficiently without danger of explosions resulting from their operation.

Another object is to provide a liquid fuel burning apparatus with a simple and efficient spark ignition means which can be economically produced and easily assembled.

Another object is to provide liquid fuel burning apparatus of the rotary fuel discharge type with spark ignition means which will function at all times during normal operation of the apparatus, and will produce an igniting spark at the proper location.

Another object is to provide liquid fuel burning apparatus with a spark ignition means so arranged as to substantially eliminate the difficulties heretofore encountered by reason of the deposits of carbon on the electrodes.

Another object is to provide liquid fuel burning apparatus having a fuel receiving hearth with an electrode body mounted in the hearth to terminate substantially at the face thereof against which the liquid fuel may be discharged.

A further object is to provide a liquid fuel burning apparatus with a spark ignition means having certain of its electrodes mounted for substantial movement after the fuel has been ignited.

With the above and other objects in view, which will be apparent from the following de-

tailed description, the present invention consists in certain features of construction and combinations of parts which will be readily understood by those skilled in the art to which the invention appertains.

In the drawings, which illustrate suitable embodiments of the invention,

Figure 1 is a perspective view of a furnace construction, portions of the same being broken away and shown in section to illustrate the application of the present invention thereto; 65

Fig. 2 is an enlarged fragmentary inner elevation of the hearth segment showing the spark ignition device attached thereto;

Fig. 3 is a fragmentary plan view of the apparatus shown in Fig. 2; 70

Fig. 4 is a section taken substantially on line 4—4 of Fig. 3, the normal position of one of the ignition electrodes being shown in broken outline;

Figs. 5 to 10, inclusive, are wiring diagrams 75 showing different methods of electric hook-up that may be used in connection with the spark ignition device;

Fig. 11 is a sectional view similar to Fig. 4 showing a modified mounting means for one of the electrodes, the operative position of the electrode being shown in broken outline;

Fig. 12 is a section taken substantially on the line 12—12 of Fig. 11;

Fig. 13 is a top plan view of a further modified 85 mounting for one of the electrodes;

Fig. 14 is a section taken on the line 14—14 of Fig. 13;

Fig. 15 is a section through a hearth segment 90 showing another means of mounting the electrodes;

Fig. 16 is a plan view of the apparatus shown in Fig. 15; and

Fig. 17 is a transverse section through a hearth ring showing the use of further modified electrodes; 95

Referring to the accompanying drawings, in which like numerals refer to like parts throughout the several views, the apparatus of the present invention is shown in connection with a liquid fuel burning apparatus of the rotary fuel discharge type. It is to be understood, however, that the present invention is adaptable to liquid fuel burning devices of types other than those shown in the drawings. 100

In the type of liquid fuel burning apparatus shown in Fig. 1 and taken for the purpose of illustration, the furnace 1 is provided with a continuous hearth segment 2 of suitable refractory 105

material which is supported well above the base of the structure on a bed 3 of refractory material that is carried by a hearth pan 4. The hearth pan 4 extends completely across the furnace 1 and is suitably supported at its periphery.

In the construction shown, the hearth segment 2 is preformed and is preferably provided with an endless channel or recess 5 of suitable shape which opens inwardly and upwardly to provide a suitable face against which the liquid fuel 10 may be discharged.

The liquid fuel is fed from a source of supply through control valves 6 to a feeder line 7 that is in communication with suitable distributing 15 mechanism 8. The distributing mechanism 8 includes a motor driven fan 9 that is horizontally mounted above the refractory bed 3 and which is arranged to distribute the liquid fuel in a suitable spray or mist against the wall of the continuous recess 5.

The present invention has to do with the means for igniting the liquid fuel as it is initially discharged against the face of the hearth segment when the distributing apparatus 8 is set 25 in operation by the demand for operation by the control mechanism 8^a (not shown in detail).

The present invention provides a practical, efficient and safe means for spark igniting the fuel, in which precautions are taken to guard 30 against explosions.

In heretofore known liquid fuel burning devices employing spark ignition there is a considerable tendency for the electrodes to become shorted by the accumulation of carbon deposits, 35 with the result that, in the case when the hearth segments become warm or hot, the fuel, upon distribution against the hearth segment, may gasify. The carbon deposits may be broken away by the weight of the fuel which is impinged thereon, and this will allow a spark to pass between the electrodes, with the result that the vaporized fuel will suddenly explode with great force. It is thus obvious that precautions 40 must be taken that the electrodes or igniters will always spark at the instant when the fuel distributing mechanism is set in operation by the 45 demand for heat.

In the drawings different types of ignition devices are shown, any one of which may be under 50 control by various electric hook-ups. These different types, however, regardless of the type of electric hook-up used, are arranged to provide safe and unfailing operation whenever the demand for operation of the fuel burning apparatus is created.

In some cases, such as in small furnace installations, it may be desirable to use a single spark ignition device, whereas in other cases it 60 may be desirable to use two or more devices.

In Fig. 1, and as shown in Figs. 5 to 10, inclusive, two such ignition devices are shown mounted diametrically opposite each other.

Referring to Figs. 1 to 4, inclusive, each ignition device includes a pair of electrodes 10 and 65 11 carried by the hearth segment 2 and spaced to obtain the best and most efficient spark.

The electrode 10 comprises a body of suitable heat resistant material, such as carborundum cement, mounted within a recess 12 formed in 70 the segment at the inner side thereof, the body being preferably recessed out in the same manner as the recess 5 to provide continuous surfaces. The body 10 should, for the most efficient operation of the apparatus, terminate substantially 75 at the face of the recess 5. It is to be un-

derstood, however, that the body may terminate slightly inwardly or outwardly of the face of the recess 5 without departing from the spirit and scope of the appended claims.

An electrode rod 13 of steel or other suitable 80 conducting material is embedded in the body 10 and extends downwardly through the hearth segment 2. The portion of the rod 13 extending beyond the segment 2 is enclosed within a suitable insulating tube 14 which preferably extends into 85 the hearth segment.

The electrode 11 which, as shown in the drawings, may be in the form of a bar of suitable heat resistant material, is mounted on a supporting head 15 that is carried at the end of an electrode 90 rod 16. The electrode rod 16 is also mounted within an insulating tube 17 that extends through a flange 18 formed on the hearth segment 2 at the inner side thereof. The electrode 11 extends over the innermost portion of the segment 2, substantially into the recess 5, and is arranged at an angle to the radius of the segment in order 95 that liquid fuel may be distributed without hindrance against the walls of the recess formed in the electrode body 10. The insulating tubes 14 and 17 may be clamped against rotation by means of a suitable clamp 19 arranged at the lower side of the segment 2.

When a single ignition device is used, such as in small furnace installations, the electrode rods 105 13 and 16 are connected through suitable lead wires to the secondary winding of a suitable transformer.

When two or more ignition devices are used, such as in large furnace installations, the ignition 110 devices may be connected in parallel and connected with a suitable transformer 20, as shown in Figs. 5, 6 and 7, or they may be connected in series and connected with the transformer 20, as shown in Figs. 8, 9 and 10. 115

In the wiring diagrams Figs. 5 to 10, inclusive, the electrodes of one ignition device are designated as 10 and 11 and the corresponding electrodes of the other ignition device are designated as 10^a and 11^a, the other parts being correspondingly numbered.

Referring to Fig. 5, the electrode 10 is connected by a suitable lead wire 21 to a pole 22 of the secondary winding 23 of the transformer 20, and the electrode 11 is connected by a suitable 125 lead wire 24 to the other pole 25 of the secondary winding 23. In a similar manner, the electrode 10^a, which corresponds to the electrode 10, is connected by a lead wire 21^a to the pole 22 of the secondary winding, and the electrode 11^a, which 130 corresponds to the electrode 11 by a lead wire 24^a to the pole 25 of the secondary winding. It will be noted in this hook-up that if the electrodes of either of the ignition devices are inoperative, the other electrodes will function as soon as a 135 demand for ignition is created. This installation insures the passage of a spark between the electrodes of either one or both of the ignition devices.

Referring to Fig. 8, the electrode 10 of the one 140 ignition device is connected by a lead wire 26 to the pole 22 of the secondary winding, and the electrode 10^a which corresponds to the electrode 10, is connected by a lead wire 27 to the other pole 25 of the secondary winding 23. The electrodes 11 and 11^a are directly connected with each other by means of a lead wire 28. In this installation the two ignition devices are in series and it will be noted that if the electrodes of one 145 of the devices is shorted, the current will flow 150 through the other device.

therethrough to the other device, with the result that a spark will be created across the electrodes of the other device.

In some installations it may be desirable to 5 employ the electrode in the form described, in which case the electrode 11 of each ignition device is held stationary in the proper position for obtaining the best and most efficient spark. In this case the head 15 is seated against the end 10 of the insulating tube 17 and held against movement relative to the tube by means of a nut 30 threaded on the electrode rod 16. Adjustment of the electrode 11 in order to obtain the proper spark gap is provided for by loosening the nut 15 30 and rotating the rod 16. The stationary arrangement of the electrode 11 is not shown in the drawings, but it is obvious that this may be obtained by merely lengthening the insulating tube 17 to bring it into engagement with the 20 head 15.

Modified arrangements of the electrodes are shown in Figs. 15 to 17, inclusive. In Figs. 16 and 15 the electrode rods 31 and 32 are arranged side by side at the inner side of the hearth segment 2. These electrode rods 31 and 32 are surrounded by suitable insulators 33 and 34 which extend through an offset portion 36 formed at the inner side of the hearth segment 2. One electrode 37 in the form of a suitable block is 25 mounted in the segment 2 in substantially the same manner as the electrode 10, and the electrode rod 31 is bent over and embedded in a portion of the electrode body 37. The electrode 38 is provided at the upper end of the electrode rod 32 in the proper sparking position with respect to the electrode 37.

In Fig. 17 the electrode rods 39 and 40 are mounted in suitable insulating tubes 41 and 42, respectively, the tube 41 being extended into the 40 body of the hearth segment 2. One electrode 43 in the form of a suitable rod or bar is joined with the rod 39 and is positioned within an opening 44 formed in the segment 2 and opening at the face of the circumferential recess 5. The electrode 43 preferably extends to and terminates 45 at the edge of the opening 44.

The other electrode 45 is attached to the electrode rod 40 in a manner similar to the electrode 11 first described.

50 The electrodes shown in Figs. 15 and 17 may be connected with a suitable transformer in any of the manners previously described or in any other desired manner.

The electrodes 11, 38 and 45 shown in Figs. 4, 55 15 and 17, may be of any suitable material, and furthermore may be of any suitable shape, such as a rod, bar or strap.

This invention further contemplates, in cases where desired, the provision of means for moving 60 one of the electrodes of each ignition device relative to the other in order to doubly insure sparking across the gap between the electrodes at the time the demand for operation of the apparatus is created.

65 One means of accomplishing this object is shown in Fig. 4. As shown in this view, the electrode rod 16 is made of a material having a low iron content and is of greater length than the surrounding insulator tube 17 in order that the rod 16 and consequently the electrode 11 may be moved relative to the tube 17. Movement in this case is provided by means of a suitable solenoid 46 surrounding the insulator tube 17, which attracts a suitable soft iron core 16^a secured to the 70 end of the rod 16. In operation, the solenoid, at

the time the demand for operation of the apparatus is created, moves the electrode 11 from its normal position to the sparking position shown in solid outline in Fig. 4. As soon as the sparking period is terminated, the supply of electrical energy to the solenoid is cut off and the electrode 11 then drops back by gravity to the normal position shown in broken outline in Fig. 4. The electrode rod 16 may be of sufficient weight as to drop back to the inoperative position or, if desired, additional weights may be attached to the rod 16 or in some cases a spring arrangement may be provided to cause the rod 16 and electrode 11 to assume the position shown in broken outline.

A suitable cap 47 may be arranged over the 80 head 15 to telescope with the projecting portion of the insulator tube 17 in order to exclude dirt, liquid fuel, and other foreign matter from the rod 16. Suitable guides are provided to prevent 85 turning movement of the electrode rod 16 relative to the axis of the tube 17, and this may be accomplished in any desired manner such as forming depressions 48 in the upper end of the tube 17 which may receive guide ribs 49 formed on the inner surface of the cap 47.

In Figs. 11 and 12 a modified arrangement is 90 shown for moving the electrode 11 relative to the electrode 10. In this arrangement the electrode rod 16 and insulating tube 17 are rigidly held together against relative movement, and the complete electrode assembly is mounted for bodily 95 tilting movement transversely of the axis thereof.

One means for accomplishing this tilting movement is to provide a sleeve 50 about the tube 17, which has oppositely disposed pivot pins 51 thereon arranged to seat in the depressions 52 formed in the hearth segment 2. A suitable protector 53 is provided to protect the pivot pins 51 from dirt and the like. In the normal position, the electrode assembly is maintained in a vertical position by gravity, in which position the electrode 11 is out of its sparking position as shown in solid outline in Fig. 11. A suitable weight 17^a may be mounted on the tube 17 to insure a vertical position of the electrode assembly.

In order to pivotally move the electrode assembly to the operative position where a spark may be passed between the electrodes 10 and 11, a solenoid 54 or other suitable means may be employed to attract a core 54^a carried by a sleeve 55 that 100 is clamped to the insulator tube 17, and thereby swing the assembly about the pins 51 as axes to the desired sparking position indicated in broken outline in Fig. 11. Means other than the electromagnets 54 may, however, be employed to provide the desired pivotal movement.

In Fig. 13, electromagnet means 56 is shown for causing a rotational movement of the electrode rod 16 in order to move the electrode 11 relative to the electrode 10. As shown in Fig. 14, 110 an arm 57 may be attached to the lower end of the rod 16 which carries a core 57^a that may be attracted by the magnet means 56. Means other than the magnet 54 may also be employed to impart the desired swinging movement to the electrode 11. A spring 58 is preferably provided to move the arm 57 and consequently the electrode 11 back to the normal position shown in dotted outline after the supply of electrical energy to the electromagnet is cut off.

115 It will be noted that the electrode assembly for the electrode 11 may be mounted for longitudinal, tilting or rotational movement. Although electrical means is shown for actuating the electrode assembly in each case, it is obvious that other 120

actuating means may be employed. This may be by mechanical means controlled by the operation of the distributing mechanism 8, by fluid pressure means, or temperature responsive means.

The operation of the apparatus is clearly obvious from the drawings and foregoing description. In each of the cases shown in Figs. 4, 11 and 13, the electrode 11 is movable with respect to the electrode 10 after the ignition period is over. Assuming for the purposes of illustration that the electrodes 10 and 11 are sparking and that they may become shorted by reason of carbon deposits, then they will no longer spark. The current may, by the operation of the system, then be cut off by the control mechanism, and as soon as this occurs the electrode 11 bodily moves relative to the electrode 10 with the result that the carbon deposit is broken.

Now assuming that the electrode 11 is in its normal position and a carbon deposit has accumulated on the electrodes to such an extent as to close the gap, then in this case as soon as the demand for ignition is created, the electrode 11 moves and breaks the carbon deposit, with the result that the electrodes will spark immediately and coincident with the starting of the liquid fuel distributing mechanism 8, and will immediately ignite the fuel that is dispelled against the hearth segment 2, and incidentally against the electrode 10.

In constructions heretofore known, the electrodes may become shorted by reason of the deposit of carbon across the spark gap when the system is normally inoperative, with the result that when the distributing mechanism 8 is set in operation the electrodes may not spark. The hearth segment 2 may be sufficiently hot so as to cause the liquid fuel to gasify, the liquid fuel during this interim being dispelled against the hearth segment and electrodes. A sufficient quantity may collect on the carbon deposit to cause the deposit to break away from the electrodes. The result is obvious, since the electrodes will then spark and as a result the gasified fuel will be ignited and produce a violent explosion, the consequences of which may be very disastrous.

It is thus seen that the device of the present invention will overcome the disadvantages heretofore known, and will provide a safe and efficient ignition system for liquid fuel burning apparatus.

Several different methods of connecting the solenoid 46 with a source of electrical energy may be employed.

Referring to Fig. 5 which is a wiring diagram for the apparatus when two ignition devices are employed, the solenoid coils 46 and 46^a may be connected in series with the transformer 20. The solenoid coils 46 and 46^a of the two ignition devices are connected in series by the wire 59, the remaining end of the one coil 46 being connected by a wire 60 into the hot line 61 of the electrical energy supply, and the other solenoid coil 46^a being connected by a wire 62 to the primary coil 63 of the transformer. In this circuit it will be seen that if either of the solenoid coils becomes inoperative or burned out, the supply of energy to the other and to the electrodes is immediately cut off. If only the one ignition device is used the wire 59 may be connected into the circuit in the same manner as the wire 62.

Referring to Fig. 6, the solenoid coils 46 and 46^a are connected in parallel with the energy supply lines 61 and 64 in advance of the transformer 20. The solenoid coil 46 is connected by

wires 65 and 66 directly with the main supply lines 61 and 64, respectively, and the solenoid coil 46^a is connected by wires 65^a and 66^a directly with the main supply lines 61 and 64, respectively. In this circuit the electrodes are all connected in parallel with the secondary winding of the transformer. It is obvious that if either of the solenoid coils burns out or is broken the other will properly function.

Referring to Fig. 7, the solenoid coils 46 and 46^a are connected in multiple series with the transformer 20. The coils 46 and 46^a are connected together by the wires 67 and 68, the wire 68 being connected into the hot supply line 61 in advance of the transformer by the wire 69, and the wire 67 being connected to the transformer by the wire 70.

It will be noted that neither the solenoid coils nor the electrodes will function in the event that the transformer is burned out.

It will be further noted that the solenoids will function independently of each other, and that each ignition device will function independently of the other.

In Figs. 8, 9 and 10, the circuits for the solenoids are the same as the circuits for the solenoids in Figs. 5, 6 and 7, respectively, the only difference in the circuits being that the electrodes in Figs. 8, 9 and 10 are in series instead of in parallel, as shown in Figs. 5, 6 and 7.

It is obvious that other combinations of circuits for the ignition devices and the solenoids may be employed, if desired.

Many advantageous features are present in this invention that are not present in liquid fuel burning devices heretofore known, and it is possible in the use of the various structures and circuits therefore shown and described herein, to use a spark ignition apparatus for fuel burners which is efficient in operation and which can be safely used without danger of explosions resulting from the deposit of carbon on the electrode.

It is to be understood that in some cases the electrodes may both be rigidly held against relative movement and that in other cases it may be desirable to mount one of the electrodes for movement relative to the other, as previously described.

Aside from the specific embodiments of the herein shown and described invention, it will be understood that numerous details of the embodiments may be altered or omitted without departing from the spirit and scope of this invention, and that I do not desire to limit the invention to the exact constructions herein set forth, as I desire to claim the invention broadly as well as specifically as indicated in the appended claims.

What I claim is:

1. In a liquid fuel burning apparatus, a pair of spaced ignition electrodes providing an air gap across which a spark may be passed to ignite the fuel, and means for moving one of said electrodes relative to the other and into an efficient sparking position spaced from the other when the fuel is to be ignited and for maintaining said last mentioned electrode in such position during the ignition period.

2. In a liquid fuel burning apparatus, a pair of spaced ignition electrodes providing an air gap across which a spark may be passed to ignite the fuel, and means for bodily moving one of said electrodes relative to and laterally of the other at the time ignition of the fuel is desired to bring said electrodes into spaced sparking relation and

for maintaining said electrodes in such relation during substantially the entire ignition period.

3. In a liquid fuel burning apparatus, a pair of spaced ignition electrodes providing an air gap across which a spark may be passed to ignite the fuel, electrical means for bodily moving one of said electrodes relative to the other at the time ignition of the fuel is desired to bring said electrodes into spaced sparking relation and for maintaining said electrodes in such relation during substantially the entire ignition period, and means for returning the said one electrode to its initial position after the ignition period is terminated.

15 4. In a liquid fuel burning apparatus, a pair of spaced ignition electrodes providing an air gap across which a spark may be passed to ignite the fuel, means for bodily tilting one of said electrodes relative to the other at the time ignition of the fuel is desired to bring said electrodes into spaced sparking relation and for maintaining said electrodes in such relation during substantially the entire ignition period, and means for returning the said one electrode to its initial position after the ignition period is terminated.

20 5. In a liquid fuel burning apparatus, a pair of spaced ignition electrodes providing an air gap across which a spark may be passed to ignite the fuel, means for rotating one of said electrodes relative to the other at the time ignition of the fuel is desired to bring said electrodes into spaced sparking relation and for maintaining said electrodes in such relation during substantially the entire ignition period, and means for returning the said one electrode to its initial position after the ignition period is terminated.

25 6. In a liquid fuel burning apparatus, ignition means comprising a hearth member, an ignition electrode mounted on said hearth member and arranged to have liquid fuel discharged against the same, a second ignition electrode spaced from said first electrode, a movable support for said second electrode, and electrical means for longitudinally moving said support to bring said electrode into proper sparking position spaced from the first electrode at the time ignition of the fuel is desired and for holding said second electrode in such position during the ignition period, said support being movable back to its initial position after the ignition period is terminated.

30 7. In a liquid fuel burning apparatus, ignition means comprising a hearth member, an ignition electrode embedded in said hearth member substantially flush with the surface thereof and arranged to have liquid fuel discharged against

the same, a second ignition electrode spaced from said first electrode, a movable support for said second electrode, an insulating tube rigidly mounted in said hearth member and surrounding said support and an electric solenoid carried by said tube for longitudinally moving said support to bring said electrode into proper sparking position at the time ignition of the fuel is desired for holding the same in such position during substantially the entire ignition period, said support being movable back to its initial position after the ignition period is terminated.

83

35 8. In a rotary oil burning apparatus, including an endless hearth member having an upstanding portion for intercepting the path of a projected stream of oil, and ignition means for igniting the oil intercepted by said upstanding portion, said ignition means including an electrode fixedly embedded in said hearth member and having a face substantially flush with the face of said upstanding portion, a second electrode spaced from the first electrode and electrical means to bodily move said second electrode into proper sparking position at the start of the ignition period and to maintain the same in such position during substantially the entire ignition period.

90

40 9. In a liquid fuel burning apparatus, a pair of spaced ignition electrodes providing an air gap across which a spark may be passed to ignite the fuel during an ignition period, means for moving one of said electrodes relative to the other and into an efficient sparking position spaced from the other and for maintaining the same in such position during substantially the entire ignition period, and means for moving the said one electrode to its original position after the ignition period is terminated.

105

45 10. In a liquid fuel burning apparatus, a pair of ignition electrodes spaced from each other at all times for igniting fuel during an ignition period, one of said electrodes being fixed, and means for moving the other of said electrodes relative to the fixed electrode into spaced sparking relation at the beginning of the ignition period.

115

50 11. In a liquid fuel burning apparatus, a pair of ignition electrodes spaced from each other at all times for igniting the fuel during an ignition period by means of a spark passed between the same, one of said electrodes being fixed and means for moving the other of said electrodes relative to the fixed electrode after the ignition period is terminated to increase the space therebetween.
